SAFETY PIN

Elsa C. Autenrieth, Phoenix, Ariz.

Application May 12, 1947, Serial No. 747,474

3 Claims. (Cl. 24—159)

1

The present invention relates to safety pins of the type having a pair of guard bars with a coacting pin proper disposed therebetween, the pin proper being affixed to one of the ends of each of said guard bars, with the free sharp end of the pin proper engageable by the free ends of the guard bars when the safety pin is in a closed condition. The principal object of the present invention is the provision of the pin proper, in the safety pin above indicated, which may be in a spaced relation from the plane of said guard bars, in order that the pin proper may pierce and engage fabric material of considerable thickness.

A still further object of the present invention is the provision in a safety pin of the type indicated, of a pin proper which normally is capable of flexing by its free end towards the free ends of said guard bars to be engaged by the latter in order that the safety pin may remain closed.

A still further object of the present invention is to generally improve the construction of a safety pin of the type above indicated.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application:

Fig. 1 is a top elevational view of the safety pin while in a closed position;

Fig. 2 is a side elevational view thereof while in a closed position;

Fig. 3 is a top elevational view thereof while in an open position;

Fig. 4 is an end elevational view of the safety pin while in a closed position;

Fig. 5 is a similar view of the safety pin while in an open position; and

Fig. 6 is a fragmentary view, partly in elevation and partly in section, the view having been taken on line 6—6 of Fig. 3.

Referring in detail to the present drawing, there is shown a safety pin, including a pair of guard bars 10, which are substantially on the same plane. Said guard bars 10 are formed out of a single metallic wire strand, embodying loop 11 from which said guard bars 10 extend. Said loop 11 imparts to said guard bars 10 a degree of flexibility and urges the latter to flex away from each other.

The free end of each of said guard bars 10 is 55

bent toward the longitudinal axial center of the safety pin and away from the plane of said guard bars 10, for effecting arm 12. Thus, the two arms 12 in the two guard bars 10 are in a raised position with relation to the plane of said guard bars 10, for the purpose which will be later apparent.

Each of said arms 12 is formed into hook 13. The two hooks 13 are effected by the right hand twist of the free ends of arms 12, with the free ends of said hooks 13 flattened to effect tongues 14.

From the hereinabove construction it will be seen that the free ends of said hooks 13 are disposed by their tongues 14 into opposite directions, by virtue of which construction hooks 13 with tongues 14 shift away from each other when manual pressure is imparted to said guard bars 10 for flexing the latter towards each other, as is clearly seen in Figs. 3 and 5.

Pin proper 15 includes leg portion 16 which is substantially in a perpendicular relation with the body portion of said pin proper 15. The free end of leg portion 16 is formed into loop 17 which encompasses loop 11 at the outer portion of the periphery of the latter. Leg portion 16 of pin 15 maintains the operative portion of the pin in a spaced relation with the plane of said guard bars 10, but in a central relation therewith.

Pin proper 15 is so formed as to normally flex, by its free sharp end 18, towards arms 12 and hooks 13. When pin proper 15 has been pierced through a fabric material, with which the safety pin was to be engaged, manual pressure upon guard bars 10 will open hooks 13 and their tongues 14, the position shown in Fig. 5, causing

the free sharp end 18 of pin 15 to spring automatically towards arms 12 and within the space defined by the spread hooks 13, to be engaged by the latter when the manual pressure at guard bars 10 is released and said guard bars 10 spring away from each other due to the action of loop 11. When said hooks 13 shift towards each other, the same embrace sharp free end 18 of pin 15 and maintain the same enclosed and guarded for preventing accidental tearing of clothes or injury to a person.

When said hooks 13 are in a closed position and in an embracing relation with said free end 18 of pin proper 15 tongues 14 are in a longitudinal position with relation to each other and with relation to pin proper 15, as is clearly seen in Fig. 1. Said tongues 14 being flat present a smooth surface preventing tear or injury. The upper ends of said hooks 13 and tongues 14 are in a spaced relation longitudinally of the pin so that the same shift without interference from

each other during their shifting movement into engagement with pin 15 or out of engagement therefrom.

Arms 12, being in a spaced relation with the plane of guard bars 10, coact with leg portion 16 for the purpose of maintaining both ends of pin proper 15 in a spaced relation with the plane of guard bars 10, thereby permitting pin proper 15 to pierce and engage fabric material of substantial thickness. Of course, when hooks 13 are opened manual pressure from the direction of the plane of said guard bars 10 should be exerted upon pin proper 15 in order to flex the same away from arms 12 so as to free it completely from hooks 13 in order that pin 15 may be driven by its free end 18 into fabric material. In fact, pin proper 15 may be angularly shifted completely out of the path of hooks 13 by manual pressure thereat to bring the free end 18 of pin 15 above the plane of tongues 14 during the process of driving the pin into a fabric material. Once said pin 15 is engaged with a fabric material, hooks 13 are then shifted away from each other by pressing guard bars 10 toward each other, and when said hooks 13 are brought to an open position the free end of the pin will automatically spring towards arms 12. The flattened condition of tongues 14 facilitate their sliding below pin 15 preparatory to shifting thereof in the opposite directions for opening hooks 13 and preparatory to the reception of the pin therewithin.

While there is described herein a preferred embodiment of the present invention, it is nevertheless to be understood that minor changes may be made therein without departing from the spirit and scope of the invention as claimed.

What I claim as new is:

1. A safety pin comprising a pair of guard bars, a loop integrally formed at one of the ends of each of said guard bars normally urging said guard bars away from each other, a pin member having an offset end affixed to said loop with the pin in a spaced relation with the plane of said guard bars and centrally thereof in position to be flexed toward said plane, arms integrally formed with the opposite ends of said guard bars and arranged in crossed relation, the free ends of said arms being spaced from the plane of said guard bars in the direction of said pin, and hooks integrally formed with the free ends of said arms and having open sides in opposed relation, when said guard bars are manually pressed toward each other against the tension of said loop said hooks shifting away from each other for receiving the free end of said pin member, the free end of said pin member being flexed toward said arms for automatically entering the space defined by said hooks when the latter remain in an open position, when the pressure upon said guard bars is released said hooks shifting toward each other for enclosing therewithin the free end of said pin member.

2. A safety pin comprising a pair of guard bars, a loop integrally formed at one of the ends of each of said guard bars normally urging said guard bars away from each other, a pin member having an offset end affixed to said loop with the pin in a spaced relation with the plane of said

guard bars and centrally thereof in position to be flexed toward said plane, arms integrally formed with the opposite ends of said guard bars and extending in crossed relation, the free ends of said arms being spaced from the plane of said guard bars in the direction of said pin, hooks integrally formed with the free ends of said arms and having open sides in opposed relation, when said guard bars are manually pressed toward each other against the tension of said loop said hooks shifting away from each other for receiving the free end of said pin member, the free end of said pin member being flexed toward said arms for automatically entering the space defined by said hooks when the latter remain in an open position, and tongues extending from the free ends of said hooks, when the pressure upon said guard bars is released said hooks and said tongues shifting toward each other for enclosing therewithin the free end of said pin member.

3. A safety pin comprising a pair of guard bars, a loop integrally formed at one of the ends of each of said guard bars normally urging said guard bars away from each other, said guard bars and said loop being formed out of a single wire strand, the major body portion of said loop being positioned between said guard bars, a pin member, said pin member including a leg portion substantially in a perpendicular relation with the remaining body portion of said pin member, the free end of said leg portion being snugly engaged to said loop at the outer portion of its perimeter and at a point at which said guard bars extend from said loop, arms integrally formed with the opposite free ends of said guard bars, said arms being bent away from the plane of said guard bars in the direction of the free end of said pin member, hooks integrally formed with and extending into opposed relation from the free ends of said arms, the leg portion of the pin member supporting the pin for flexing action toward the arms, when said guard bars are manually pressed toward each other against the tensioning action of said loop said hooks shifting away from each other for receiving the free end of said pin member, the free end of said pin member being flexed toward said arms for automatically entering the space defined by said hooks when the latter remain in an open position, said leg portion and said arms maintaining the remaining portion of said pin member in a spaced and substantially parallel relation with the plane of said guard bars, and tongues extending from the free ends of said hooks, when the pressure upon said guard bars is released said hooks and said tongues shifting toward each other for enclosing therewithin the free end of the remaining portion of said pin member.
